STRIPPER ELEMENT FOR MEAT SKINNING MACHINE

Ray T. Townsend, 3131 Fleur Drive,
Des Moines, Iowa 50321

Filed Aug. 19, 1974, Ser. No. 498,255

Term of patent 14 years

Int. Cl. D8—05

U.S. CL. D11—1 A

Fig. 1

Fig. 2

Fig. 3

Fig. 5

Fig. 6

Fig. 4

FIG. 1 is a perspective view of a stripper element for meat skinning machine showing my new design;

FIG. 2 is a typical side elevational view thereof;

FIG. 3 is a front view thereof as seen from the left hand side of FIG. 2;

FIG. 4 is a rearward view as seen from the right hand side of FIG. 2;

FIG. 5 is an upper plan view thereof;

FIG. 6 is a bottom plan view thereof.

I claim:

The ornamental design for a stripper element for meat skinning machine, as substantially shown and described.
